Atty.

UNITED STATES PATENT OFFICE.

WALTER B. NICHOLS, OF DANVILLE, KENTUCKY.

CAR-COUPING.

SPECIFICATION forming part of Letters Patent No. 278,728, dated June 5, 1883.

Application filed March 29, 1883. (No model.)

To all whom it may concern:

Be it known that I, WALTER B. NICHOLS, a citizen of the United States, residing at Danville, Kentucky, have invented a new and useful Improvement in Car-Couplings, of which the following is a specification.

This invention relates to attachments for rendering the ordinary pin-and-link couplings of railway-cars "automatic" or "self-coupling," so as to obviate going between the cars to couple them, and for uncoupling the same from either side or the top of freight-cars.

Heretofore various devices have been invented and patented, as means for accomplishing the result above indicated; but, so far as I am informed, none of them have been introduced into common or general use, while the pin-and-link coupling is still exclusively used on many railways.

The general object of the present invention is to accomplish said results by means as simple and inexpensive as to facilitate their introduction into actual use. Its objects, more specifically, are, first, to automatically elevate and drop the pin, which is to be dropped by devices adapted to be attached to ordinary draw-heads and to coact with ordinary coupling pins and links; secondly, to do this by devices so attached to the respective draw-heads that they can be readily interchanged should a car be turned in making up a train; thirdly, to support the link in horizontal position, and at the best height within the scope of the draw-head, by means involving no peculiarity in or change of the latter; and, fourthly, to facilitate uncoupling freight-cars, as aforesaid.

This present invention consists in certain attachments or auxiliaries, in combination with ordinary draw-heads furnished with coupling-pins and a coupling-link, whereby I accomplish the above-named objects, respectively, as hereinafter more particularly set forth and claimed.

On a sheet of drawings accompanying this specification, as part thereof, Figure 1 is a top view of a pair of draw-heads provided with my attachments; and Fig. 2 is a longitudinal section on the line 2 2, Fig. 1, illustrating the automatic coupling operation. Fig. 3 is a top view of a part. Fig. 4 is a transverse section on the line 4 4, Fig. 1, showing another part

more fully. Fig. 5 is a perspective view of the latter modified. Fig. 6 is a perspective view of another part, and Fig. 7 is a face view of the said uncoupling device.

55

Like letters of reference indicate corresponding parts in the several figures.

A, B represent a pair of ordinary draw-heads, furnished with coupling-pins *a* *b* and with a link, C, as means for coupling two cars of a railway-train. To render such draw-heads self-coupling, I provide one of them, A, with a rigidly-attached "pin-lifter," D, preferably of spring-steel, having a lifting-incline, *c*, as its principal feature. This projects from beneath the draw-head and in line therewith to a sufficient distance, determined by the abruptness of its incline. The other draw-head, B, is provided with a gravitating "pin-carrier," E, to coact with said pin-lifter. This pin-carrier has a hole, *d*, in its top, through which the coupling-pin *b* passes into the pin-holes of the draw-head, the head of the pin resting on the top of the pin-carrier, while beneath the draw-head the pin-carrier is adapted, preferably by means of an anti-friction roller, *e*, to engage with said lifting-incline *c*, and be elevated, together with the pin which it carries, by means of the pin-lifter D before the draw-heads come together in the coupling operation.

80

The parts above named are shown in Fig. 1 and in full lines in Fig. 2 in their relative positions when the pin-lifter D, attached by the link-carrying draw-head, comes in contact with the pin-carrier E. This is seen in Fig. 2, where I further show in dotted lines the relative positions of the parts when the pin *b* is fully lifted. This is accomplished before the link C enters the stationary draw-head, so that the link shall freely enter beneath the elevated pin *b*. The latter is dropped an instant later, the summit *f* of the lifter passing said roller *e*, and allowing the latter to descend into a play-space, *g*, formed by a deep curve in the lifter near the draw-head to which it is attached. A notch or slot, *h*, cut in the lifter at said summit thereof, accommodates the protruding end of the lowered pin *b*, should the link C be short. The summit *f* has been extended, so to speak, as shown in Fig. 2, by a nearly horizontal, or it may be a horizontal, portion, so as to support the pin an instant in its highest position,

95

100

and the lower extremity, *i*, of the lifter has been bent, so as to be more abrupt than the incline *c*, to extend the scope of a given length of lifter to the utmost limit. This extremity of the lifter would not strike a roller *e* ordinarily; but should the latter be carried by a very low draw-head it might thus be caught by the lifter, when it would otherwise be passed. I do not, however, consider these features last named material; nor do I propose to use said abrupt extremity *i* save on an elastic lifter.

A car furnished with my attachments would, it will be understood, have a pin-lifter, *D*, at one end, and a pin-carrier, *E*, on its other draw-head. To provide for readily interchanging these attachments should a car become turned end for end in making up a train, both of said attachments are made removable, and each draw-head is adapted to carry either one, as I will now set forth.

For the attachment of said pin-lifter *D* the draw-heads are simply provided, for example, with holes *j* in the bottom of each, drilled and tapped to receive thumb-screws *k*, and lifted therewith, while the pin-lifter is constructed with slotted holes *l*, so as to escape from the heads of these screws when they are partly turned. Applied to the screws in the same condition of the latter the lifter is quickly clamped, so as to project rigidly, by tightening the screws. Other known fastenings may be used as substitutes for screws and slotted holes with like effect, and these are considered mechanical equivalents of the latter for the purposes of my invention.

For the attachment of said pin-carrier *E*, vertical guides *m* are secured by screws to the respective sides of each draw-head. The pin-carrier *E* shown in Figs. 1, 2 and 4, is released by unscrewing a thumb-nut, *n*, which permits the withdrawal of a headed and shouldered rod, *o*, upon which the roller *e*, being a sleeve-roller, rotates in operation. The body of the pin-holder may now be slipped off, one draw-head and applied in front of the guides *m* of the other, and here secured in an instant by inserting said rod *o* through the roller and applying said nut *n*, the shoulder of the rod serving to limit the clamping, so that the carrier and its roller shall work freely. In the modification illustrated by Fig. 5 the body of the pin-carrier is provided with a hinge, *p*, so that the roller may be solid, and permanently attached at one end—by a swivel-head, *q*, for example—the holder being fastened in place by a split pin, *r*, or a thumb-nut or other equivalent fastening applied to the free end of the roller.

To support the link *C* in horizontal position at the proper height to insure its proper entrance into the opposite draw-head, *B*, the link-carrying draw-head *A* is provided with a link-holder, *F*, Figs. 1, 2, and 6, in the form of a spiral spring, *s*, of sufficiently-stiff steel, coiled openly, and of proper dimensions to spring into and out of the mouth of the draw-

head, with disks *t* fixedly attached to its respective ends, and constructed with central holes to receive the coupling-pin *a* belonging to this draw-head. The link-holder is thus secured within the draw-head, and its displacement by jarring is precluded by the coupling-pin. The link *C* is inserted between any two of the coils of the link-holder *F*, the latter being sprung in tightly enough to preclude displacement thereof during this operation, and the pin is then dropped into place. The link-holder is now effective, as illustrated by Figs. 1 and 2. It may be quickly transferred, with the pin-lifter *D*, to another draw-head, should this become necessary, being removable bodily, as illustrated by Fig. 3.

My attachments are primarily applicable to freight-cars. For uncoupling these a double-ended hand-lever, *G*, Fig. 7, is attached to the end of the car by a pivot-plate, *H*, and connected with the coupling-pin *b* by a chain, *I*. The lower end of this chain passes through a staple, *u*, which confines it to the middle of the car end, and it terminates in a ring, *v*, which embraces the pin loosely below the top of the pin-carrier *E*. The upper end of the chain terminates in another ring, *v*². This embraces a rod, *w*, which is attached at both ends to the hand-lever *G*, and is provided with bends near the respective handles of the latter, to hold the ring *v*² until the pin is withdrawn from the link. A slight further movement of the lever in the same direction disengages the ring, which then slips along the rod to the bend at the lower end of the lever. Which-ever end of the lever is uppermost is pulled or pushed downward, or the opposite end is lifted, as may be most convenient. A stop-lug, *x*, may be formed on the face of the pivot-plate *H* to limit the motion of the hand-lever. The lever is shown in its respective positions of rest by full and dotted lines in Fig. 7.

Having thus described my invention, I claim as new and desire to secure by Letters Patent—

1. In combination with a pair of draw-heads furnished with ordinary coupling-pins and an ordinary coupling-link, a pin-lifter, *D*, constructed with a lifting-incline, *c*, and curved to form a play-space, *g*, and attached rigidly to the bottom of one draw-head, and a gravitating pin-carrier, *E*, mounted upon the opposite draw-head, and having a horizontal roller, *e*, beneath the latter to coact with said lifting-incline, substantially as herein specified.

2. In combination with a pair of draw-heads furnished with ordinary coupling-pins and an ordinary coupling-link, the pin-lifter *D* and gravitating pin-carrier *E*, constructed and operating substantially as herein specified, and removably attached to the respective draw-heads, the latter being adapted for the attachment of either, substantially as shown, for the purposes set forth.

3. The removable link-holder *F*, composed of a spiral spring, *s*, and a pair of end plates, *t*, the latter having central holes, in combi-

nation with a draw-head, A, a coupling-pin, *a*, and a coupling-link, C, for holding the latter in the manner set forth.

as shown, for uncoupling freight-cars in the manner set forth.

4. The double-ended hand-lever G, provided with the rod *w*, having holding-bends, as described, in combination with the pivot-plate H, chain I, and a coupling-pin, *b*, substantially

WALTER B. NICHOLS.
